UNITED STATES PATENT OFFICE.

COURTNEY CONOVER, OF PHILADELPHIA, PENNSYLVANIA, AND HARRY D. GIBBS, OF SAN FRANCISCO, CALIFORNIA.

PROCESS FOR THE MANUFACTURE OF ANTHRAQUINONE.

1,303,168.

Specification of Letters Patent.

Patented May 6, 1919.

No Drawing.

Application filed June 7, 1917. Serial No. 173,405.

(FILED UNDER THE ACT OF MARCH 3, 1883, 22 STAT. L., 625.)

To all whom it may concern:

Be it known that we, COURTNEY CONOVER and HARRY D. GIBBS, citizens of the United States of America, and employees of the 5 Department of Agriculture, residing in the city of Philadelphia, county of Philadelphia, State of Pennsylvania, and in the city of San Francisco, county of San Francisco, State of California, respectively, (whose 10 post-office address is Washington, D. C.) have invented a new and useful Process for the Manufacture of Anthraquinone.

This application is made under the act of 15 March 3, 1883, chapter 143 (22 Stat., 625), and the invention herein described and claimed may be used by the Government of the United States or any of its officers or employees in the prosecution of work for the Government, or any person in the 20 United States, without payment to us of any royalty.

Our invention relates to a process for the manufacture of anthraquinone from anthracene.

25 It is well known that anthraquinone is commonly produced by the oxidation of anthracene in an extremely fine state of division by means of chromic acid. In this process the reduction of the anthracene to the fine state of division is difficult and expensive, and further the chromic acid subsequently used for oxidation is a costly reagent. The object of our invention is to provide a process for the manufacture of 30 anthraquinone which will be free from the objectionable features of the processes employed at present.

Our invention consists in the production 40 of anthraquinone from anthracene by heating the anthracene until it passes into the vapor phase, mixing this anthracene vapor with an oxygen-containing gas mixture, forcing this mixture of gases into close contact with finely divided oxids of the metals of the 45 sixth group of the periodic system, viz: chromium, molybdenum, tungsten, and uranium, heated to a temperature ranging from 250° C. to 650° C., under which treatment the anthracene is partially oxidized to form 50 the valuable product named.

To illustrate the practical operation of our process we shall describe in detail the preferred procedure. Anthracene is melted

and is caused to flow continuously at a measured rate into a heated chamber where it is 55 volatilized. This vapor of anthracene is then mixed with air in excess of the proportion theoretically required to oxidize anthracene to anthraquinone. The mixture of air and anthracene vapor is passed into a 60 reaction chamber maintained at a temperature ranging from 350° to 550° C., the preferred temperature being 500° C. In this chamber the gas mixture is forced into close contact with oxids of a metal of the sixth 65 group of the periodic system (preferably oxids of molybdenum) in the form of a fine powder. This powder is supported on trays or on a porous material where, by mechanical means, the current of mixed gases is 70 forced through it. The gases are kept under pressure only sufficient to cause them to flow continuously through the reaction chamber. The products of the reaction, together with unchanged anthracene, are 75 condensed, and the anthraquinone is separated from the unchanged anthracene and other substances, if any, by well-known processes.

We have discovered that the process as above described may be varied in many 80 ways and yet will produce anthraquinone. Thus, oxygen may be substituted wholly or in part for air, or air may be mixed with a gas which is relatively inert under the conditions obtaining in the process. The 85 oxids of the metals of the sixth group of the periodic system, viz: chromium, molybdenum, tungsten, and uranium, may be mixed with or combined with each other or with other substances, such as other metallic 90 oxids, or with asbestos, pumice stone, or other materials. The gas mixture may be brought in contact with or forced through the catalyst in many different ways. The proportion of anthracene vapor to the oxygen-containing 95 gas mixture may be varied within wide limits. Materials containing anthracene, together with the substances commonly associated with it may be used instead of pure anthracene. And the reaction products may be separated by various well-known means.

Having thus described our invention, we claim—

1. A process for the manufacture of anthraquinone, which process consists in sub-

jecting anthracene in the gaseous state and mixed with an oxygen-containing gas mixture, to the action of oxids of a metal of the sixth group of the periodic system heated to 5 temperatures ranging from 350° to 550° centigrade.

2. A process for the manufacture of anthraquinone, which process consists in subjecting anthracene in the gaseous state and 10 mixed with atmosphere air to the action of oxids of a metal of the sixth group of the periodic system heated to temperatures ranging from 350° to 550° centigrade.

3. A process for the manufacture of anthraquinone, which process consists in subjecting anthracene in the gaseous state and 15 mixed with an oxygen-containing gas mixture, to the action of oxids of a metal of the sixth group of the periodic system heated to

temperatures ranging from 250° to 650° 20 centigrade.

4. A process for the manufacture of anthraquinone, which process consists in subjecting, while in the gaseous state and mixed with an oxygen-containing gas mixture, anthracene, together with other substances derived from coal-tar, to the action of oxids of a metal of the sixth group of the periodic system heated to temperatures ranging from 250° to 650° centigrade. 25

In testimony whereof we affix our signatures in the presence of two subscribing witnesses.

COURTNEY CONOVER.
HARRY D. GIBBS.
